VACUUM BREAKER

Edward W. N. Boosey, Detroit, Mich.

Application February 19, 1944, Serial No. 523,110

3 Claims. (Cl. 137—69)

1

This invention relates to a vacuum breaker for use in the water supply system of a building including a container in which water may be contaminated as for instance through the washing of articles therein.

The purpose of the invention is to provide means automatically functioning to permit flow of air from atmosphere to the water supply conduit in the event of a less than atmospheric pressure condition occurring in the supply conduit thereby preventing withdrawal of contaminated water from a container into the supply system under influence of the reduced pressure condition in the supply system.

In many instances in homes, hospitals, or other buildings in which various types of articles require to be cleaned, water is supplied thereto through a conduit opening to the container below the liquid level therein and a less than atmospheric pressure condition in the supply conduit tends to draw impure water from the container into the supply line and thus contaminate water in the supply system as is hereinafter more fully described.

A structure embodying my invention is shown in the accompanying drawing in which—

Fig. 1 is a vertical section showing the preferred form of my improved automatic relief valve.

Fig. 2 is a cross section of the regulator mechanism taken on line 2—2 of Fig. 1.

Fig. 3 is a cross section taken on line 3—3 of Fig. 1.

In the preferred form of the invention shown in Fig. 1 the water supply conduit is indicated at 1 to which my improved vacuum relief valve is connected by the threaded hub 2 of the valve body 3. The regulator mechanism is indicated generally at 4 and includes a cylindrical body provided with a rectangular projecting end portion 5 which may be rotated by the nut-like element 6 having a rectangular recess in its inner end in which the end 5 of the valve is positioned. The element 6 is also provided with a squared end portion 7 by which it may be turned. Other means for rotation of the member 6 may be utilized.

The valve body 3 is of a chambered form and has a recess on the side opposite the nut 6 to receive the rounded end 8 of the body of the regulator which has an opening in its inner end as indicated by dotted lines 9 and through which the ball 10 may be introduced into the interior thereof. The regulator body has an elongated slot 11 in its lower side, in the position shown

in Fig. 1, of less width and greater length than the diameter of the ball. The opposite side of the regulator body has an aperture 12 of a diameter slightly less than the diameter of the ball and additional apertures 13 and 14 on opposite sides thereof, the purpose of which is hereinafter described.

The said valve body 3 has a threaded terminal conduit portion 15, which may be of any desired length and functions as an extension of the conduit 2, on which is threaded a chambered member 16 having a series of apertures 17 adjacent its larger upper end and above the lower end of the threaded terminal portion 15.

The said conduit portion 15 adjacent its upper end is provided with a transverse wall having apertures 18 therein and a central internally threaded aperture to receive the threaded upper end of a tube 19 centrally disposed in the body 16 and terminating at its lower end at or adjacent to the lower end of the body or casing 16. The said lower end of the body 16 is threaded to receive the threaded end of the discharge conduit 20 leading to a container, not here shown. The tube 19 has a series of vertically spaced apertures 21 therein preferably arranged spirally about the tube as indicated.

Under the described arrangement of parts and with the valve member 4 in the position shown, a pressure condition less than atmospheric pressure in the conduit 1 tends to draw air through the ports 17 and thence through the apertures 18 and thence through the slot 11 in the regulator. If the reduced pressure condition in the supply conduit is sufficiently great, the ball 10 is moved to close the aperture 12. Under such condition however air continues to pass through the apertures 13 and 14 to the supply conduit. The purpose of this arrangement is to gradually eliminate the detrimental effect of a less than atmospheric pressure condition in the supply conduit.

It is further to be observed that air may also pass through the apertures 17 in the body member 16 and thence through the apertures 21 to the interior of the tube 19. These apertures 21 are preferably arranged in longitudinally spaced relation and as the water level in the coned member 16 is lowered, an increasing number of the apertures 21 are opened to flow of air.

55 This arrangement for air flow, which includes the apertures 17, 18 and 21 arranged as hereinbefore described, provides for an increase in volume of flow of air to the supply conduit as the water level in the body 16 decreases. The introduction of air eliminates the detrimental

effect of a less than atmospheric pressure condition in the supply conduit.

It is further preferable to provide an air deflecting rib or ribs 22 in the body member 16 below the air inlet apertures 17. The said rib or ribs provide an air deflection means tending to direct the same to the passageway 23 to which the apertures 18 are open.

By the arrangement of parts as described the air flow into the plumbing system through the aperture 21 is increased in volume as the water level in the chambered member 16 is lowered by reason of its flow by gravity to the container.

It is also to be observed that the tube 19 having the apertures 21 therein adapts the device for use with a closed container with which the conduit 20 may be connected and wherein air under pressure may accumulate. The arrangement provides for an escape of air from the container without the necessity of use of a separate relief valve as is commonly the practice. It is also pointed out that the film of water on the exterior of the tube 19 during discharge of water to either an open or closed container tends to prevent discharge of water from the interior of the tube through the apertures 21 and also tends to prevent splashing which would ordinarily occur without the described arrangement which provides a film of water from the apertures 23 around the exterior of the inlet end of the tube 19.

Having thus fully described my invention, its utility and mode of operation, what I claim and desire to secure by Letters Patent of the United States is:

1. A vacuum breaker positionable between spaced parts of a water supply conduit having a terminal portion discharging to a container below the liquid level therein, comprising a chambered body member having apertures adjacent its upper end providing for flow of air thereto and supported in spaced relation on the conduit, said supply conduit terminating in said body member below the apertures therein, an open ended tube supported within said terminal portion of the conduit in peripherally spaced relation therewith and providing for flow of air through the apertures and thence to between the terminal portion of the conduit and the tube, to the supply conduit under influence of a reduced

pressure condition therein below atmospheric pressure, said tube having a series of apertures in its wall in spaced relation longitudinally thereof of providing for increase of flow of air into the tube as the water level decreases in the body member.

2. A vacuum breaker positionable between vertically spaced parts of a water supply conduit discharging to a container below the liquid level therein, comprising a chambered body member having apertures therein adjacent its upper end providing for ingress of air from atmosphere to the body member under influence of a less than atmospheric pressure condition in the supply conduit, the supply conduit extending into the body member to a point below the said apertures, an open ended tube supported in peripherally spaced relation with the last named portion of the conduit and extending into said body member to a point adjacent the lower end thereof, the said tube having a series of apertures in its wall in longitudinally spaced relation, the arrangement providing for flow of air into the body member and thence through the space between the conduit and the tube into the supply conduit under influence of a less than atmospheric pressure condition therein the said apertures in the tube providing for increased flow of air to the supply conduit as the water level decreases in the body member.

3. A vacuum breaker positionable between vertically spaced parts of a water supply conduit having a terminal portion discharging to a container below the normal liquid level therein, comprising a chambered body member supported between the spaced parts of the conduit and having apertures therein adjacent its upper end, the conduit terminating within the body member below the upper end thereof, an open ended tube supported within said terminal portion of the conduit in peripherally spaced relation therewith and providing for flow of air from atmosphere to the supply conduit under influence of a pressure condition therein below atmospheric pressure, the said tube having a series of apertures therein in longitudinally spaced relation providing for flow of air to the supply conduit.

EDWARD W. N. BOOSEY.
